(57) **CLAIM**

The ornamental design for a personal alarm, as shown and described.

DESCRIPTION

FIG. 1 is a perspective view of a personal alarm;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof;
FIG. 7 is a bottom plan view thereof;
FIG. 8 is another perspective view thereof; and,
FIG. 9 is an enlarged view of portion of FIG. 8.
The evenly broken lines where present illustrate portions of
the personal alarm that form no part of the claimed design.
